WITNESS:

UNITED STATES PATENT OFFICE.

DAVID BAUGHMAN, OF PIERCE, FLORIDA.

BUILDING CONSTRUCTION.

1,390,951.

Specification of Letters Patent. Patented Sept. 13, 1921.

Application filed February 7, 1920. Serial No. 356,890.

To all whom it may concern:

Be it known that I, DAVID BAUGHMAN, a citizen of the United States, residing at Pierce, in the county of Polk and State of Florida, have invented new and useful Improvements in Building Construction, of which the following is a specification.

My present invention has reference to a building construction.

10 The primary object is to produce a means whereby a building can be erected in an easy, inexpensive, strong and efficient manner.

A further object is to construct a building in which the outer walls and foundation are 15 formed of poured concrete, and in which the wall studs have means received in and reinforcing the concrete walls, and in addition thereto bracing the supporting studs, the spaces between the walls and the plaster on 20 the studs providing dead air chambers that will prevent dampness to the interior of the building as well as protect the same against exterior heat or cold.

Other objects and advantages will present themselves as the nature of the invention is better understood, reference being had to the accompanying drawings in which there is illustrated a satisfactory embodiment of the improvement reduced to practice, and in which:—

Figure 1 is a detail vertical longitudinal sectional view through a portion of a building construction in accordance with this invention.

35 Fig. 2 is a horizontal sectional view therethrough.

The walls and foundation of the building are formed by poured concrete. The foundation walls may be reinforced in the ordinary manner, but the side walls are reinforced in a particular manner which will hereinafter be set forth.

When the foundation wall, indicated by the numeral 1, in Fig. 1 of the drawings is 45 formed the boards constituting the molds therefor are removed, and on the upper and straight edge 2 of the said foundation wall I lay a sill 3. It will be noted that the sill is disposed adjacent to the inner face of the 50 foundation wall 1. On the sill, at its outer corner I place a vertically arranged horizontally disposed board or plate 4. This plate may be secured to the sill in any desired or preferred manner, and against this plate 55 abut the floor joists 5 that have their ends

resting on the sill 3. On the joists there is nailed, first the sub-floor 6, and on the sub-floor the main floor 7. On the first sub-floor, which has its end resting on the upper edge of the plate 4, I arrange a horizontally disposed plate 8. It is to be noted that the outer edge of the plate 8 is flush with the outer edge of the plate 4 and the outer edge of the sill 3. These elements permit of the forming of the lower portion of the side 65 walls 9 of the building. The concrete is poured between the mentioned members and the outer board of the mold is, of course, suitably secured. Before the lower portion of the wall is formed, or after the forming 70 thereof, as desired, there is positioned on the plate 8 spaced studs 10. These studs are arranged a suitable distance inward of the edge of the plate 8, the plate 8 being in reality a 2 x 4 stud. The studs 10 being 75 also of 2 x 4 dimensions will have their outer edges projecting a slight distance outward of the plate or stud 8. The distance between the inner edge of the studs 10 and the edge of the plate or stud 8 equals the thickness of 80 the plaster 11. After the studs 10 are erected, and preferably secured to the plate 8 I arrange, at preferably equi-distantly spaced intervals around all of the studs, wire members 12. These wire members are 85 drawn taut and are retained on the studs through the medium of staples 13 that enter the studs and, of course, surround the wires. At the corner of the building, as illustrated in Fig. 2 of the drawings the end studs 10, 90 are braced by a vertical board 14 which is arranged between the jointed faces thereof, and against these boards at the corners of the building the concrete engages. Thus it will be noted that the concrete at the corners is 95 of a greater thickness than the side walls, and the wire members 12 being rounded. The said corners materially reinforce the same.

Between the horizontally arranged wires 100 12 I secure in the outer faces of the studs 10 preferably angularly arranged crossing nails 15. The nails do not entirely enter the studs, but as a matter of fact extend therebeyond for the major portions of their lengths, and the said nails provide both reinforcing elements for the concrete walls and means for effectively sustaining the said walls on the studs. When the wires and nails are positioned as described, the inner 105 110

mold boards are arranged between the studs and the outer mold boards are arranged flush with the outer face of the base 1. The plastic material is then poured between the mold 5 boards and allowed to settle and this is repeated until the walls 9 are completely erected.

While in the drawings I have illustrated a one story building, it is to be understood 10 that with my construction buildings of any number of stories may be constructed. It is, of course, also to be understood that the walls may be of varying thicknesses, and that the outer edges of the studs 10 entering 15 the concrete at the inner face of the walls provided thereby serve as additional means for bracing or reinforcing the concrete, as only the parts of the concrete wall disposed between the studs are braced against lateral 20 movement by the studs. The improvement is not only designed for dwellings but in the construction of barns, and in fact in the construction of any class of buildings, and in Fig. 1 of the drawings the device illustrates the manner in which a barn may be 25 constructed. On the top of the studs and secured thereto is a 2 x 4 plate 16. Resting on this plate and secured thereto is the wall plate 17. On the wall plate are the 30 ceiling joists 18, and secured to the angle ends of the ceiling joists 18 and received in notches in the wall plate 17 are the roof rafters 19.

It is believed that the foregoing description, when taken in connection with the 35 drawings will fully set forth the construction and will render the simplicity and advantages thereof apparent to those skilled

in the art to which such inventions appertain.

Having thus described the invention, what I claim is:—

In a poured concrete building construction, a concrete base, a wooden sill of a less width than the base arranged on the base in a line with the inner edge thereof, a vertically arranged board resting on and in a line with the outer edge of the sill, and floor joists resting on the sill and contacting the board, a plate resting on the joists and having its outer edge in a line with the outer face of the board, vertically disposed spaced studs resting on and secured to the plate and having their inner edges disposed inwardly from the inner edge of the plate and their outer edges disposed outwardly over the outer edge of the plate, a plate having its edges flush with the inner and outer faces of the studs resting on and secured to said studs, horizontally arranged equi-distantly spaced wire members on the outer faces of the studs, means securing the wires to the respective studs, crossed nails driven in the outer face of the studs between the wire members, the sill board and plate providing inner mold members for the plastic wall built outward therefrom on the base, and the remaining inner mold members designed to be received between the spaced studs and have their outer surfaces in a line with the referred to inner permanent mold, whereby the outer portions of the studs are embedded in the concrete wall.

In testimony whereof I affix my signature.

DAVID BAUGHMAN
